UNITED STATES PATENT OFFICE.

HARRY J. HICK, OF ALLIANCE, OHIO, ASSIGNOR TO THE McCASKEY REGISTER COMPANY, (INCORPORATED IN 1914,) OF ALLIANCE, OHIO, A CORPORATION OF OHIO.

INDEX-FRAME.

1,280,732.

Specification of Letters Patent.

Patented Oct. 8, 1918.

Application filed June 15, 1916. Serial No. 103,735.

To all whom it may concern:

Be it known that I, HARRY J. HICK, a citizen of the United States, residing at Alliance, in the county of Stark and State of 5 Ohio, have invented certain new and useful Improvements in Index-Frames, of which the following is a specification.

The invention relates to frames for holding a plurality of index cards for use in 10 connection with filing appliances and the like, and the object of the improvement is to construct the frame in such a manner that the cards can be readily inserted, and when inserted will be securely retained therein; 15 and from which the cards can be readily removed for shifting to another position, or for cancellation; without the use of special tools or appliances for inserting or removing the cards.

20 The objects of the invention thus briefly stated, are attained by mounting a plurality of parallel stiff wires or round rods upon the face of a back plate, which is preferably made of sheet metal having a plurality of 25 rows of spaced eyes or loops struck up from the body thereof for receiving and holding the wires or rods in contact with the face of the plate.

In the accompanying drawings the invention 30 is illustrated as embodied in an index frame provided with hinge members on one edge for mounting in a filing appliance of the hinged-frame type, in which embodiment of the improvement the index cards are 35 used to indicate the various credit accounts or other records which are carried in the filing appliance.

In the drawings, Figure 1, is a front or 40 face elevation of the index frame; Fig. 2, a fragmentary enlarged section on line 2—2, Fig. 1;

Fig. 3, a similar view on line 3—3, Fig. 1; and

Fig. 4, a fragmentary enlarged perspective view showing the method of removing 45 an index slip.

Similar numerals refer to similar parts throughout the drawings.

The frame includes the back plate 1 which 50 is preferably made of sheet metal and is provided with suitable stiffening ribs 2, 2^a and 2^b on its rims or edges for holding the plate in a flat plane.

A plurality of loops 3 are cut along the 55 sides and struck forward from the body of

the plate to form the eyes 4 for receiving and holding the round stiff wires or rods 5 upon the face of the plate.

The eye loops 3 are arranged in parallel vertical rows on the face of the plate and are spaced apart to form a series of parallel rows of laterally alined eyes 4 into which the wires or rods 5 are entered by being inserted endwise from one side of the frame to the other; and the wires or rods are preferably cut to lengths equal to the distance between the rim ribs 2^b on the ends of the frame. It will be understood that the wires or rods are inserted in the eyes before at least one of these end ribs is secured to the 70 frame, after which the end ribs retain the wires from longitudinal displacement.

This construction and arrangement forms between vertical rows of eye loops, a series of vertical rows or columns of facets 6 upon the face of the back plate, each of said facets being bounded above and below by one of the transverse wires or rods which are mounted on the face of the plate. The cylindrical surfaces of the wires or rods form 80 dovetail grooves in conjunction with the face of the plate for receiving the opposite longitudinal edges of the flexible index cards 7 inserted in the recessed facets, formed by the wires, and it is evident that the index cards 85 may be readily secured in said facets by merely entering one longitudinal edge of a card in the dove-tail groove formed by the roundness of one wire and the face of the plate, and then pressing the other longitudinal edge into the opposing dovetail groove formed by the roundness of the other wire and the face of the plate, which is readily done by the mere pressure of one's finger or finger nail; it being understood 95 that the index cards are formed of suitable length and width to neatly enter the recessed facets and to be retained in position by the dovetail grooves formed between the wires and the face of the back plate.

For removing an index card it is only necessary to insert the finger nail underneath one corner or end of the card, or preferably the point of a pen knife blade may be used for this purpose, as shown in Fig. 4; and the card can then be readily removed from the recessed facet formed by the wires. It will be understood that the roundness of the retaining wires permits the longitudinal edges of the index cards to be entered and 110

removed from the dovetail recesses formed underneath the sides of the wires without mutilating or tearing the edges of the cards, so that the same can be removed from one recess and inserted in another without destroying the card.

I claim:

1. A frame for index cards including a sheet metal back plate, a plurality of rows of laterally alined eye-loops struck from the body of the plate, and a plurality of spaced parallel round rods mounted in the eyes of the loops upon the face of the plate.
2. A frame for index cards including a sheet metal back plate, a plurality of eye-loops struck from the body of the plate, and a plurality of spaced round rods mounted in the eyes of the loops upon the face of the plate.
3. A frame for index cards including a back plate, a plurality of rows of eye-loops on the face of the plate, and a plurality of parallel round rods mounted in the eyes of the loops upon the face of the plate.

4. A frame for index cards including a back plate, a plurality of laterally alined eye-loops on the face of the plate and a plurality of round rods mounted in the eyes of the loops upon the face of the plate.

5. A frame for index cards including a back plate, a plurality of eye-loops struck up from the surface of the plate and a plurality of rods mounted in the eyes of the loops upon the face of the plate for receiving index cards between them.

6. A frame for index cards including a back plate, and a plurality of spaced parallel round rods mounted on and in contact with the face of the plate.

7. A frame comprising a back-plate, round rods secured thereto in parallel relation with each other, and flexible indicia adapted to extend between the rods so that their edges will extend into the gradually diminishing slots between the rods and the back-plate and be thereby secured against sidewise displacement.

HARRY J. HICK.
